APPARATUS FOR FLANGING SHEET METAL STRIPS

Reginald Perkins, Hayes, England, assignor to
The Fairey Aviation Company Limited, Hayes,
Middlesex, England

Application March 8, 1946, Serial No. 652,951
In Great Britain January 25, 1945

4 Claims. (Cl. 153—3)

1

This invention relates to means for flanging sheet metal plates, strips or the like whether carried out by draw bench methods, or by means such as are described and claimed in the specification of application for Letters Patent Serial No. 524,280, filed Feb. 28, 1944, and issued as Patent No. 2,420,064 on May 6, 1947, and has for its principal object to produce flanged work of varying width and a further object is to form flanges at varying angles.

According to the present invention the work is clamped between two plates, strips or the like, one of which, hereinafter called a former, corresponds in cross-sectional shape with the sectional configuration, at different transverse planes, of the work to be produced, in that the work may be bent round it, and the other of which, hereinafter called a control plate, also corresponds in cross-sectional shape with said work, but in an inverse sense, and these plates, strips or the like, together with the work, are arranged to be drawn through a pair of dies adapted to press the work against one side, or against the opposite sides, of the former, each of said dies being adapted to co-operate with the side of the control plate remote therefrom in order that the width of the finished work may vary at predetermined positions along its length.

For this purpose the width of the control plate varies in an inverse sense as compared with that of the former; that is to say that where at any position along its length the width of the former is increased to produce outward bulges on the flanges of the finished work, or is increased at one side of a median line to produce an outward bulge on one flange of the finished work, the width of the control plate, at a corresponding position along its length, is decreased at both sides or at one side, as the case may be, and, conversely, the width of the control plate is increased if concavities, or a concavity be required in the finished work.

Preferably the dies are mounted in die holders having oppositely directed, overlapping or interdigitated, limbs which pass under (or over) the control plate and carry rubbing blocks, anti-friction rollers, or the like, to co-operate with the sides of the control plate.

If the flanges to be produced on the work are oppositely directed from the plane of the central zone or web two formers are required, one of which may be integral with the control plate.

If it be desired to produce on the finished work a flange which is inclined to the general plane of the work at an angle other than a right angle,

2

or if it be desired to bend the work gradually round the former, the dies may be carried in semi-cylindrical seatings in the die holders so that they may accommodate themselves automatically to the required angularity.

For a more ready comprehension of the invention reference is to be had to the accompanying drawings wherein Figure 1 is a perspective view of a typical former and control plate for the production of a curved component (shown in broken lines) of varying section; Figure 2 is a perspective view of a former, control plate and straight component of varying section, the former, control plate and component being separated from one another for the sake of clearness; Figure 3 is a perspective view showing three pairs of dies in conjunction with a former, control plate and component which are of simpler configuration than that shown in Figure 2 and are depicted in broken lines; Figures 4 and 5 are exploded views showing details of the parts of the two dies of a pair, respectively; Figure 6 is a perspective view of a former control plate and component of a more complicated varying section, the former, control plate and component being separated from one another for the sake of clearness; Figure 7 is a perspective view similar to Figure 3 but with two formers and with dies arranged for the production on the component of flanges directed oppositely from the plane of the central zone or web of the component; and Figures 8 and 9 are exploded views showing details of the parts of the two modified dies of a pair, respectively.

As shown, a former consists of a bar *a* of metal 35 the shape of which corresponds with that of the trough of a channel section piece of work *b* and may be symmetrical, as shown in Figure 2, or 40 asymmetrical, as shown in Figures 1, 3, 6 and 7, about a longitudinal median plane, that is to say, as shown in Figure 1 the bar *a* may be of constant cross sectional shape, but of increasing width, one side being shaped for the production of a simple flange *c* at one side of the work *b* and a stepped flange *c* at the other side thereof. 45 Again, as shown in Figure 2, the bar *a* may have lateral swellings *d*, *d* to form outward bulges *e*, *e* on the flanges *c*, *c* of the work to be produced and these bulges *e*, *e* may be symmetrical, as shown in Figure 2, as asymmetrical. Similarly, 50 it may have lateral concavities *f*, *f* to permit corresponding concavities *g*, *g* to be produced in the flanges *c*, *c*.

The control plate consists of a similar bar *h* of steel, but the variations of its width are inverse 55 as compared with those of the former. This is

shown clearly in Figure 2 where it will be seen that concavities *j*, *j* at the sides of the control plate *h* correspond, in position and inversely in shape, with the lateral swellings *d*, *d* on the former *a* and *e*, *e* on the work *b* and lateral swellings *k*, *k* at the sides of the control plate *h* correspond, in position and inversely in shape, with the concavities *f*, *f* at the sides of the former *a* and *g*, *g* at the sides of the work *b*.

For accurate assembly the control plate *h* is provided near its ends with upstanding locating pins *m*, *m*, Figure 2, and the former has corresponding holes *n*, *n* to receive the pins *m*, *m*. The blank for the work *b* consists of a suitably shaped plate, strip or the like of metal which is placed in position between the former *a* and control plate *h* so that its lateral margins project beyond the former *a* to an extent corresponding with the flanges *c*, *c* to be formed, and means (not shown) may be provided for clamping together the former *a*, the blank and the control plate *h*. As shown, especially in Figures 4 and 5 each of the die holders is of L-shape generally and is arranged with its horizontal limb *o* and *o'* respectively extending across and under the control plate *h* and with its upright limb *p* and *p'* respectively extending upwards at one side of the control plate *h*, the blank and the former *a*. Each upright limb *p*, *p'* has a head *q* and *q'* respectively which overhangs somewhat the horizontal limb *o* or *o'* respectively to present in the re-entrant angle, a seating for a die block *r* which is located by retaining screws *s* and is supported, at the trailing face of the die holder by a thrust plate *t* held by screws *u* . . . to said holder. At its leading end the lower inner corner of the die block *r* is rounded spherically as at *v*, Figure 4, to bend the marginal portion of the blank through a right angle and against the side of the former *a* when the work is drawn through the dies, as explained hereinafter.

The horizontal limb *o* of one die holder is bifurcated, as shown in Figure 4, to receive the horizontal limb *o'* of the other die holder shown in Figure 5, and the single limb of said other die holder has upstanding therefrom a curved face rubbing block *w*. Integral with the limbs of the bifurcated die holder are two upstanding steps *x*, *x* against which, and bridging the bifurcation, is located a curved face rubbing block *y* secured in position by dowel pins *z*, *z* or like means, the curved faces of these rubbing blocks *w* and *y* being inwardly directed, i. e., towards one another.

Near their upper and lower parts the die holders are bored to receive guide rods *||*, *||* so that, as shown in Figure 3, when the two die holders are assembled in interdigitated relationship they may be slid away from one another to permit the ends of the control plate *h* and the former *a* to be introduced therebetween, the upstanding rubbing blocks *w* and *y* contacting with the lateral faces of the control plate *h* each rubbing block with that lateral face remote from the die to which the rubbing block appertains. When the end of the blank is pulled against and between the dies *r*, *r* the die holders tend to separate, but, as such separation is prevented by the coaction of the rubbing blocks *w* and *y* with the lateral faces of the control plate *h*, the dies *r*, *r* act on the margins of the blank and turn them through a right angle against the sides of the former *a*, the die holders being allowed to slide on the guide rods *||*, *||* and move away from one another when their rubbing blocks *w* and *y* enter con-

cavities *j*, *j* in the lateral faces of the control plate *h*, and the die holders *o*, *p* and *o'*, *p'* being forced towards one another when their rubbing blocks *w* and *y* encounter bulges *k*, *k* on said lateral faces thus producing bulges *e*, *e* or concavities *g*, *g* (as the case may be) from or in the flanges *c*, *c* of the work *b* as the control plate *h*, the work *b* and the former *a* are drawn between the die holders *o*, *p* and *o'*, *p'*.

10 The drawing of the control plate *h*, the work *b* and the former *a* between the die holders *o*, *p*, *o'*, *p'* may be effected by means of the vice grab on a draw bench or otherwise conveniently such as described in the specification of application for Letters Patent Serial No. 524,280, for instance

15 the former may have one or more series of holes in which the teeth of the gear wheel or wheels may engage. Alternatively, the modified means described in the specification accompanying application for Letters Patent Serial No. 652,950, filed March 8, 1946, may be employed.

20 If the work *b* is to have two flanges *c'* and *c''*, Figure 7, extending oppositely from the plane of its central zone two formers *a'* and *a''* must be used one *a'* above the blank *b* as just described and the other *a''* between the blank *b* and the control plate *h*, it being understood that the die holders *o*, *p*, *o'*, *p'* must be suitably gapped to accommodate the extra thickness of metal.

25 Figures 7, 8 and 9 show modifications which are necessary if a flange on the work is to be pressed into position gradually or if a flange on the finished work is to be inclined to the central zone at an angle other than a right angle, e. g. as shown in Figure 6. In this event, the corresponding die block *r'* is semi-cylindrical at its back, as shown at 12, Figures 8 and 9, the die holder is formed with a semi-cylindrical seating 12, and the die block *r'* is held against the seating 12 by die-retaining screws 13 passing through arcuate slots 14 in the thrust plate *t'* and in a similar plate *t''* formed integrally at the leading face of the die holder. In this event the die face *v'*, Figure 8, is situated below the level of the

30 axis of the die block *r'*, i. e. at the lower part of its diameter and the corresponding lateral face of the former *a'* or *a''* must be suitably angled if an inclined flange is to be produced on the finished work, as shown in Figure 6, the width of the control plate *h* corresponding inversely, with the width of the former *a'* or *a''* at its median plane, i. e. halfway up the inclined face. If, however, the use of a semi-cylindrically seated die block *r'* is to enable a flange *c* on the work to be pressed into position gradually a series of dies must be provided to enable the cross section of the work to be varied, progressively, e. g. as is the case in the flanging means described in the specification of application for Letters Patent Serial No. 524,280, and the lengths of the horizontal limbs *o* and *o'* respectively of the series of die holders should be varied correspondingly.

35 I claim:

40 1. Improved means for flanging sheet metal plates, strips and the like comprising two plates, strips or the like between which the work is clamped, one of which constitutes a former and the other of which constitutes a control plate, and 45 one or more pairs of dies through which the work may be drawn, the former corresponding in cross-sectional shape with the sectional configuration, at different transverse planes, of the work to be produced, and the control plate also corresponding in cross-sectional shape with the work, but in

an inverse sense, the dies being adapted to press the work against one side, or against the opposite sides, of the former, and each of the dies being adapted to co-operate with the side of the control plate remote therefrom in order that the width of the finished work may vary at pre-determined positions along its length.

2. Improved means for flanging sheet metal plates, strips and the like, as claimed in claim 1, wherein the dies are mounted in die holders having oppositely directed, overlapping or inter-digitated, limbs which pass transversely of the control plate and co-operate with the sides of the control plate.

3. Improved means for flanging sheet metal plates, strips and the like, as claimed in claim 2, wherein two formers are provided in order that there may be produced on the work flanges which are oppositely directed from the plane of the central zone or web of the work.

4. Improved means for flanging sheet metal plates, strips and the like, as claimed in claim 3, wherein the dies are carried in semi-cylindrical seatings in the die holders so that they may accommodate themselves automatically to the an-

gularity required to enable the production on the finished work of a flange which is inclined to the general plane of the work at an angle other than a right angle, or if it be desired to bend the work gradually round the former.

REGINALD PERKINS.
